DANIEL MAPES, OF UPPER MONTCLAIR, NEW JERSEY, ASSIGNOR TO WALTER KIDDE & COMPANY, INC., OF NEW YORK, N. Y., A CORPORATION OF NEW YORK

DISCHARGE CONTROL MEANS FOR STORED PRESSURE MEDIUM CONTAINERS

Application filed April 9, 1932. Serial No. 604,334.

The present invention relates to fire extinguishing apparatus employing a fire extinguishing liquid propelled by a medium stored under pressure in a cartridge or other container and embodies more specifically means for effecting a predetermined and definitely controlled rate of discharge of the pressure medium whereby to obtain a uniform discharge of the liquid fire extinguishing medium over a definite period of time.

The difficulty has heretofore been encountered, due to uncontrolled release of the pressure medium, that the discharge of the liquid fire extinguishing medium has been non-uniform, resulting at the start in a strong stream of considerable range which undesirably weakens during the period of desired effective discharge.

It has been proposed to overcome this difficulty by creating a more or less accurate discharge orifice at the time of effecting discharge of the pressure medium, but this solution at its best is unsatisfactory because of dependence of the accuracy of the orifice upon the disturbing factor of corrosion and upon other circumstances not controllable between the time of manufacture and the time of use.

The present invention on the other hand broadly contemplates the provision of means having a predetermined fixed discharge controlling effect whereby to effect a definitely controlled discharge over a definite period of time.

More specifically the invention contemplates the provision of metering devices on pressure cartridges or containers comprising orifices, passages or equivalent discharge controlling means having predetermined or pre-formed and/or tested discharge controlling effects.

A desirable advantage of the present invention is that the discharge of the pressure medium at a definitely controlled rate prevents the building up of undue pressure in the liquid fire extinguishing medium container, such as might rupture the container.

Further objects and features of the invention, not specifically enumerated above, will be apparent as the invention is described in

greater detail in connection with the accompanying drawings, wherein:

Figure 1 is a view in vertical, central section of the upper portion of a pressure cartridge and metering device in accordance with the invention.

Figure 2 is a central longitudinal sectional view of an extinguisher embodying the invention.

Figure 3 is a view in central longitudinal section of a portion of the extinguisher shown in Figure 2 when in its inverted or operated position.

Figure 4 is a view similar to Figure 1 showing a modified type of metering device.

Figure 5 is another view similar to Figure 1 showing still another form of metering device.

In Figure 2 of the drawings there is represented at 1 a standard shell or container for holding a liquid fire extinguishing medium, such as water, calcium chloride solution or other suitable fire extinguishing medium, which is filled into the container up to the level of the filling indicator 2. The shell is provided with a handle 3 for carrying the extinguisher in an erect position, another handle 4 for carrying the extinguisher in an inverted position, a strainer 5, an outlet elbow 6, a standard hose 7 coupled to the outlet elbow and having a discharge nozzle 8. A cage comprising an upper flange 9, a bottom plate 10 and suspension rods 11 is supported upon a shoulder 12 in the neck of the shell and in turn supports a cartridge 13 containing a medium under pressure, such as liquid carbon dioxide, for propelling the liquid fire extinguishing medium from the shell. The cartridge 13 is provided with a closure member 14 containing means for effecting release of the pressure medium from the cartridge, said releasing means becoming operative upon inversion and jarring of the shell, whereby to cause forcible engagement of the releasing means with a projection 15 formed on a cap 16 and extending within the shell. The cap 16 is threaded to the neck of the shell with an intervening gasket 17 which not only effects a leakage-tight joint with the shell, but secures the flange 9 of the cage against move-

ment. The cap 16 is otherwise standard, being provided with a rim 18 for carrying the extinguisher in an upright position and for effecting rotation of the cap.

In Figure 1 the reference numerals 13 and 14 have the same significance as in Figure 2. The closure member 14 is provided with a threaded extension 19 adapted to engage, leakage-tight, cooperating threads in the neck of the cartridge 13. At the lower end of the threaded extension 19 is shown a strainer 20 in the form of a screen which is shown secured to the extension by rolling over a lip 21, the extension being provided with a central bore generally represented by the reference numeral 22. The passage 22 not only communicates through the strainer 20 with the interior of the cartridge 13 but also communicates with a passage 23 terminating in a chamber generally indicated by the reference numeral 24.

The passage 23 is adapted to be closed by a thimble 25 which is provided with threads 26 engaging cooperating threads in the coupling 14. The thimble 25 is provided with a central passage 27 which is normally closed by a frangible disc 28 and a gasket or washer 29 of suitable material, the frangible disc and gasket being secured in position by rolling over a lip 30 on the lower reduced portion of the thimble 25. The gasket 29 should be of a material which will seal the pressure medium within the container 13 when the thimble 25 is tightened to bring the gasket 29 into forcible contact with the seating surface 31 encircling the passage 23.

The metering device for the embodiment of the invention shown in Figure 1 is constituted by the frangible disc puncturing element 32, which is not only provided with a chamfered cutting edge at its lowermost extremity, but which passes with a close-working fit within the passage 27 and which is reamed out at 33 to a closely predetermined diameter. In consequence of this construction, when the frangible disc 28 is ruptured and the pressure medium is released, the pressure medium cannot escape past the close-working fit between the puncturing element 32 and the passage 27, but can only discharge through the predetermined passage 33 so that the desired definitely controlled discharge over a definite period of time is effected.

The puncturing element 32 is normally maintained in its uppermost position by means of a flange 34 secured thereto and pressed upwardly by a spring 35 against a stop ring 36 which is secured against a shoulder 37 by rolling over of the metal 38 of the closure member 14. The assembly of the unit is completed by the insertion of a disc 39 of fragile material such as thin bakelite or glass, a water-tight seal being effected at 40 by means of sealing wax or other suitable material, the purpose of the disc 39 being to

70 maintain the disc puncturing element and metering device free from corrosion and to serve, when fractured, as an indication that the cartridge has been emptied, either accidentally, as by rupturing of the frangible disc 28 upon development of excessive pressure within the cartridge, or intentionally, in the manner about to be described.

75 With the extinguisher in its erect position as shown in Figure 2, operation of the extinguisher involves overturning it, grasping it by the handle 4, and jarring the extinguisher as by striking it on the floor or ground, so as to cause the disc 39 (Figure 1) to be fractured by forcible contact with the projection 15 on the inner side of the cap 16 and the frangible disc 28 to be punctured by the element 32, in connection with which it should be noted that Figure 3 illustrates the inverted 80 operated position of the extinguisher. As shown in both Figures 2 and 3 the innermost end of the projection 15 is cross-grooved at 41 to provide free escape of the pressure medium from the metering device passage 33 through the opening 42 in the stop ring 36 and 85 thence past the fractured disc 39 into the liquid extinguishing medium in the shell 1, through which the pressure medium rises to the upper surface of the liquid medium, upon which the pressure acts to propel the liquid 90 medium through the hose 7 and nozzle 8.

95 In view of the fact that the diameter of the passage 33 can be accurately controlled at the time of manufacture, and in fact, subjected to a discharge rate test, it will be apparent that the desired rate of discharge can be obtained whenever an extinguisher is used so that a stream of liquid fire extinguishing medium of uniform range can be maintained over a desired predetermined period of time.

100 With reference to Figures 4 and 5, those elements corresponding exactly to the same elements in Figure 1 have been similarly numbered and will not be described again.

105 In Figure 4 the metering device is shown in the form of an accurately proportioned orifice 43 formed in a disc 44 secured, leakage-tight, in the passage 22. With this construction the same advantages are had as are obtained with the construction shown in Figure 1 but in the present embodiment of the invention the passage 45 through the disc puncturing element 32 is larger than the orifice 43 and exerts no 110 controlling effect on the rate of discharge.

115 In Figure 5 the metering device is shown in the form of bulky porous material 46, such as closely packed steel wool or closely packed fibrous material such as cotton or blotting material. In this construction a screen 47 is preferably employed and the desired predetermined quantity of porous material is inserted in the passage 22 before the strainer 20 is secured in position in the manner described in connection with Figure 1. In this 120 construction, as with the construction in Fig- 125

ure 4, the passage 45 in the disc puncturing element 32 does not exert a controlling effect on the rate of discharge. The controlling effect of the material 46, while capable of being carefully predetermined, can be checked by testing the entire assembly of the closure member 14 in a suitable fixture which, however, does not form part of the present invention.

10 In Figures 1 and 5 the reference numeral 48 represents one or more passages through which the initial charging of the cartridge takes place, at which time the thimble 25 is raised so that the pressure medium may pass 15 between the gasket 29 and the seating surface 31. The corresponding passage in Figure 4 is not shown and is accordingly to be assumed to be outside of the section shown.

It should be noted that the apparatus herein-described involves certain other features which are not unitary with the present invention and which accordingly will be made the subject-matter of further applications.

From the foregoing description it will be seen that I have made decided improvements in stored pressure cartridges and containers for use with pressure propelled liquid fire extinguishing mediums, not only in respect of specific forms of construction, but also broadly in respect of providing predetermined means for accurately controlling the discharge rates of pressure mediums stored in pressure containers. It will accordingly be noted that, while the invention has been described with specific reference to the accompanying drawings and the application of the invention to fire extinguishing apparatus, it is not to be limited, save as defined in the appended claims.

40 1. As an article of manufacture a vessel for containing a medium under pressure, said vessel being formed with at least one end open, a closure member for an open end of the vessel, a passage through said closure member, means to normally close the passage against the escape of the pressure medium and to permit the escape of the medium when desired, and means to control the rate of discharge of the medium from the vessel independently of the extent of opening of said passage by said last named means comprising a controlling element having a preformed fixed flow control characteristic.

45 2. The combination with a vessel for containing a medium under pressure having means to effect release of the medium therefrom, of means to control the rate of discharge of the medium from the vessel independently of the extent of opening of the vessel by the means to effect release of the medium comprising a controlling element having a preformed fixed flow control characteristic.

50 3. As an article of manufacture a vessel for containing a medium under pressure, said vessel being formed with at least one end

open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of opening of said passage by said last named means, comprising a controlling element having a preformed fixed flow control characteristic.

4. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of opening of said passage by said last named means comprising a controlling element having a preformed fixed flow control characteristic, said controlling means comprising a restricted passage having a preformed accurately controlled cross-sectional area.

5. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of opening of said passage by said last named means comprising a controlling element having a preformed fixed flow control characteristic, said controlling means comprising an orifice having a preformed accurately controlled cross-sectional area.

6. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of opening of said passage by said last named means comprising a controlling element having a preformed fixed flow control characteristic, said controlling means comprising bulky porous ma-

terial having a predetermined rate of discharge controlling effect.

7. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of opening of said passage by said last named means comprising a controlling element having a preformed fixed flow control characteristic, said controlling means comprising bulky porous material having a tested rate of discharge controlling effect.

8. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, and means within the closure member to control the rate of discharge of the medium from the vessel independently of the extent of the opening of said passage by said last named means comprising a controlling element having a preformed fixed flow control characteristic, said controlling means being situated within the portion of the aforesaid passage in the closure member between said vessel and the means closing said passage against the escape of the pressure medium.

9. As an article of manufacture a vessel for containing a medium under pressure, said vessel being formed with at least one end open, a closure member for an open end of the vessel, a passage through said closure member, a frangible disc within the closure member to close the passage against the escape of the pressure medium, securing means to secure the disc over the end of the passage, a passage through the securing means, and puncturing means to puncture the disc to permit the escape of the medium when desired, said puncturing means being provided with a

passage of preformed accurately controlled cross-section to permit definitely controlled discharge of the medium therethrough independently of the extent of opening of said frangible disc by said puncturing means and being formed for a close-working fit within the passage in the securing means to prevent escape of the medium past the close-working fit to an extent which would negative the controlling effect of the passage in the puncturing means.

10. As an article of manufacture a vessel for containing a medium under pressure, said vessel being formed with at least one end open, a closure member for an open end of the vessel, a passage through said closure member, means within the closure member to close the passage against the escape of the pressure medium and to permit the escape of the medium when desired, means within the closure member to control the rate of discharge of the medium from the vessel independently of the extent of opening of said passage by said last named means comprising a controlling element having a preformed fixed flow control characteristic, said controlling means comprising a restricted passage having a preformed accurately controlled cross-sectional area, and straining means within the closure member for preventing conveyance to the restricted passage of material which would clog the restricted passage and destroy its controlling effect.

11. As an article of manufacturing a vessel for containing a medium under pressure, said vessel being formed with at least one end open, a closure member for an open end of the vessel, a passage through said closure member, means within the closure member to close the passage against the escape of the pressure medium and to permit the escape of the medium when desired, means within the closure member to control the rate of discharge of the medium from the vessel independently of the extent of opening of said passage by said last named means comprising a controlling element having a preformed fixed flow control characteristic, and straining means within the closure member for preventing conveyance to the controlling means of material which would clog it and destroy its controlling effect.

DANIEL MAPES.
